UNITED STATES PATENT OFFICE

GEORGE WASHINGTON KNOX, OF OKLAHOMA CITY, OKLAHOMA

CONDUCTOR FOR OIL-WELL HEATERS

Application filed February 21, 1927. Serial No. 169,983.

This invention relates to methods of and means for heating the products in oil wells for the purpose of increasing the flow or capacity of such wells and facilitating the delivery of the products above ground.

It is well known that after a flush production in oil wells, there is usually a gradual decline of production until the operations of the wells become unprofitable but it has been found in practice that supposedly depleted wells may be revived and restored to profitable production, through a method and means of heating the deposits in the bottoms of the wells, such bottoms being usually termed the "shot holes," and the surrounding oil producing sands of formations.

The sluggish character of the wells leading to the apparent depletion is due to a number of causes, but the most prevalent cause of such sluggishness is the presence of heavy oil, or the presence of paraffin, which retards the flow of oil into the shot hole from the oil producing sands and lessens the productivity of the well.

It has been found in practice and it is well known that the application of heat to the contents of the shot hole and oil producing formations surrounding increases the fluidity of the said contents and brings it in condition where it can be expeditiously pumped and this, of course, results in reducing the pressure against the inflow of oil in the well, from the surrounding oil producing formations.

It is an object of this invention to provide means for heating the contents of the shot hole and for displacing the deposits immediately in contact with the heater in order that deposits of lower temperature may be brought into contact with the heater successively and displaced as heated so that the said heated deposits may be circulated and transmit heat to the oil sands and the heavy hydrocarbons be taken up by the pump or other applied methods and delivered above ground.

It is a further object of this invention to produce a heater for an oil well in which delivery of the current or the circuit for the current includes a well casing as one of its

paths, or in which the said circuit includes the pump tubing and the sucker rod as one of its paths, or a circuit which includes the casing as one of the paths or leads and the tubing and the sucker rod as another of said leads.

It is furthermore an object of this invention to produce novel means whereby the circuits to and from the heater are segregated against accidental shorting, yet including contacts and connections by which a circuit through these instrumentalities may be maintained.

It is still a further object of this invention to provide a tubing having a plurality of insulators removably applied to it, and effective to prevent shorting of the circuit between the tube and the casing and to equip the pump operating means and the head of the casing with means for insuring proper operation of the heater.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a sectional view of a well casing, showing a heater installed in the shot hole associated with the casing;

Figure 2 illustrates a sectional view of the device on the line 2—2 of Fig. 1;

Figure 3 illustrates an enlarged detail sectional view of a casing and the tube, with an insulator applied thereto;

Figure 4 illustrates a sectional view of the tube, indicating the relation of the standing and working valves of the pumping barrel or apparatus to the tube;

Figure 5 illustrates a sectional view of the heater insulator;

Figure 6 illustrates an enlarged sectional view of the insulator and the tube and parts associated with them;

Figure 7 illustrates a detail sectional view of the coupling for the pump;

Figure 8 illustrates an insulated pipe joint;

5 Figure 9 illustrates a sectional view on the line 9—9 of Fig. 1;

Figure 10 illustrates a detail view of the polish rod stuffing box; and

10 Figure 11 illustrates a modified insulating unit.

In these drawings, 15 denotes a well casing extending to a shot hole 16, and provided with a head 17, known in practice as a head control, and a gas line 18 communicates with the interior of the casing as a part of the usual equipment. The tube 18 may be of known construction and, of course, is made up of lengths of tubing having appropriate couplings 19, it being 15 the usual practice to have such tube extend practically the full length of the well in order that the working and standing valves of the pumping barrel will be submerged in the deposit of the shot hole.

25 The tube has insulation 17^a where it passes through the head, and the tube is insulated from the casing, in the present embodiment of the invention, by a plurality of insulators which are preferably of uniform construction, and a description of one of them 30 will suffice as a disclosure of their structure and means of anchorage, to one skilled in the art.

35 Preferably, each insulator consists of a cylindrical central portion 21 of slightly greater diameter than the tube, and a plurality of radially disposed fins 22 project from the said central portion, but they terminate in spaced relation to the internal 40 bore of the casing. They are in such relation to the casing that lateral movement of the tube relative to the casing will cause the insulators to engage the casing and prevent the tube from contact with the casing. The 45 number of fins is preferably minimized in order that free circulation of gas or water may be permitted in the casing, and the fact that the fins do not extend to the wall of the casing also affords a clearance for the 50 circulation of gas and water so that pressure may be relieved through the gas line 18'. Preferably the insulators when applied to the tubing are retained just above the joints between the sections of the tubing, 55 although, of course, this is not an absolute necessity. In the present embodiment of the invention, however, the insulators are shown as encircling the tube at the joint or coupling on a gasket 18^a, which will serve to prevent displacement of the insulator in a 60 downward direction on the tube, as when the tube is being pulled from the casing. Furthermore, the fins have rounded corners which serve to prevent lodging on shoulders 65 or other obstructions at the joints of the

casing. Each insulator is preferably held in place by a substantially constructed wedge 18^b with corrugations or crimps 18^c that are tapered from the upper end to the lower end of the wedge and the wedge is inserted between the insulator and the tube forced therein by mechanical pressure, to a degree which will insure retention of the insulator by friction.

70 An insulator is provided at the lower end of the tube and, in the present embodiment of the invention, it comprises a cylindrical core 23 having a plurality of radially disposed ribs 24 whose edges are notched to form seats 25 in which the resistance element or wire 26 is seated. The seats in the ribs are differently spaced in the several ribs in order that when the resistance element is wound on the insulator, it will be in spiral form. In order to produce this result, the location of the seats from the upper ends of the ribs is progressively increased around the insulator, as will be understood.

75 The number of ribs may vary and whereas four such ribs have been found sufficient as anchorages for the resistance element, more than that number may be employed, as illustrated in Fig. 5. Preferably, the ribs have holes such as 27 in them, 80 through which ties may be introduced, for securing the resistance element and preventing its displacement in the event of the insulator becoming fractured or impaired.

85 When installing the insulator on the tube, 90 guard insulators 28 and 29 may be stationed above and below the end of the insulator.

95 The resistance element 26 is shown as connected to the tube by a conductor 30, whereas the other end of the resistance element is connected by a cable 31 to a brush or wiper 32 which is in electrical contact with the casing. The brush or wiper 32 comprises a plurality of blades preferably of resilient metal, whose central portions 33 are secured on a tubular insulator 34, which 100 insulator encircles the tube 18, by which the brush or wiper is supported. The electrical connection between the cable 31 and the casing may, of course be of different constructions, but the one here shown has been 105 found satisfactory in use and it comprises a series of blades of resilient metal, as stated, whose ends are bowed or bent outwardly from the central anchored portions so that the said blades bear against the inner wall 110 of the casing.

115 As a means for supplying current to the heater, a suitable source of electricity, such as a generator 35, may be employed, having 120 a conductor 36 leading to the casing and a conductor 37 leading to the tube.

125 The polish rod 38 attached to the upper end of the sucker or pumping rods operates through a head or stuffing box 39 at the top 130

of the tube, and the oil outlet pipe 40 has an insulated joint 41 with the nipple or outlet pipe 42 leading from the tube. The polish rod is connected to the walking beam or rod operating mechanism 43 through means of trunnions 44, which trunnions project from a housing 45. Apertured insulators 46 and 47 extend downwardly and upwardly, respectively, from the housing 45 and the rod 38 extends through said insulators. The rod is further insulated from the trunnions by a cylindrical insulator 48 fitting in the housing and surrounding a collar 49 between the insulators 46 and 47, to which the rod 38 is secured by a fastening 50, such as a set screw or the like. A removably applied plate 51 on the housing bears against the upper insulator 47 and by this means the parts are held assembled. The insulation for the trunnions just described is to insulate the rods from the casing and ground, which forms one part of the circuit through the walking beam or the casing. The insulation for this part of the structure will, of course, be of such strength and ruggedness that the lifting action of the beam and the thrust action thereof will in nowise damage, fracture, or destroy it.

In order to insure high conductivity between the heater and the source of electricity and the ground, the sucker rods and working valve are provided with a contact 52, here shown as an electrical contactor which moves in contact with the inner wall of the tube 18, and this contactor constitutes a member of a circuit through the working valve and the sucker rod. The stuffing box 39 at the upper end of the tube through which the polish rod operates is also provided with electrical contactors 53 which act as conductors between the polish rod and the tubing and they insure that the rod with the tube assumes the full portion of the electrical load.

In order to guard against a person coming in contact with the operating parts of the mechanism just described, a shield 54 may be built or placed around the head of the casing and the connections for the conductors of electricity and other parts of the mechanism. This shield may be in the nature of an expanded metal column, or it may be of any appropriate and efficient type without regard to material, its shape or other details.

While the inventor has supplied herein a description which to some extent is directed to the details of construction and relation of parts, it will be understood that changes in the proportions and the types of insulators and joints may be changed to suit particular requirements and duties, and the inventor does not wish to be limited with respect to these features, except as they may be included in the claims of the patent.

While the specification has been directed more particularly to the description of the

circuits in association with the heater of the open type, the same mechanism and circuit forming means have been used with equal success in heaters of the closed type which are employed in wells having salt water and other mixtures which preclude the use of heaters of the open type.

The insulators 28 and 29 have preferably vertically disposed holes 28^a near their edges, through which the conductors may be threaded from the heater. Any other desirable form of connection to any type heater may be employed, either at will, or as the occasion demands.

In Fig. 11 the insulator 54 is shown as applied to the coupling 55 and the coupling may be provided with an annular channel 56 forming a seat for the insulator, and there may be a corrugated joint 57 between the coupling and the insulator which will increase the resistance to displacement of the insulator with respect to the coupling.

I claim:

1. An oil well heater comprising an electric heater, a well casing, pump tube therein, means for insulating the pump tube from the well casing, means for electrically connecting the heater and casing including brushes mounted on and insulated from the tube engaging the said casing, and a conductor from said brushes to the heater, means for electrically connecting the heater and tube, and conductors from a source of electricity to the casing and tube.

2. In an oil well heater, an electric heater, a well casing, a pump tube therein, means for insulating the tube from the casing, means for electrically connecting the heater and casing, means for electrically connecting the heater and tube, a sucker rod in the tube, an electrical contact carried by the sucker rod engaging the tube, an electrical connection between the tube and the sucker rod at approximately the top of said tube, and conductors from a source of electricity to the casing and tube.

3. A pump tube, a sucker rod therein, means for electrically connecting the said tube and rod, an electric heater at the lower end of the tube, a source of electricity, and an electric circuit including said source of electricity and heater, one element of which circuit comprises the tube and rod.

4. In a heater for oil wells, a casing, a tube therein, an electric heater in the oil well, means for establishing a circuit to the heater through the said casing and tube, means for insulating the tube from the casing consisting of a plurality of insulating elements applied to the tube, and a wedge interposed between the tube and the insulator for frictionally retaining the insulator in place.

5. In a heater for oil wells, a casing, a tube therein, an electric heater in the oil

- well, means for establishing a circuit to the heater through the said casing and tube, means for insulating the tube from the casing consisting of a plurality of insulating elements applied to the tube, and means for holding each insulator on the tube at different positions of adjustment, said means comprising a substantially cylindrical wedge having downwardly tapered ribs adapted to be forced between the tube and insulator.
6. In a heater for oil wells, a casing, a tube therein, a sucker rod, an electric heater and a circuit for current for the heater, one element of which consists of the casing and the other the tube and sucker rod, and means for insulating the sucker rod from its associated elements.
